UNITED STATES PATENT OFFICE.

WILLIAM H. SOMMER, OF PEORIA, ILLINOIS, ASSIGNOR, BY MESNE ASSIGNMENTS, TO THE FIRST TRUST & SAVINGS COMPANY, OF CLEVELAND, OHIO, A CORPORATION OF OHIO, AND JOHN A. CHAPMAN, OF CHICAGO, ILLINOIS, TRUSTEES.

WIRE FENCE.

1,378,489.

Specification of Letters Patent. Patented May 17, 1921.

Application filed October 27, 1917. Serial No. 198,782.

To all whom it may concern:

Be it known that I, WILLIAM H. SOMMER, a citizen of the United States, residing at Peoria, in the county of Peoria and State 5 of Illinois, have invented new and useful Improvements in Wire Fences, of which the following is a specification.

This invention has reference to improvements in wire fences, and relates particularly to the construction of the line or running wires and the wrapping of the stay or 10 picket wires therearound.

The invention has for its object to provide a fence with top and bottom running 15 wires which are oval or oblong in cross-section around which the ends of round stay or picket wires are wrapped at an angle to the vertical; or to provide a fence, the intermediate running wires of which, as well as 20 the top and bottom wires, are oval or oblong in cross-section, around which the ends of round short sections forming the stay or picket wires are wrapped.

Further objects, as well as the advantages 25 resulting from the use of line or running wires which are oval or oblong in cross-section will appear in the following description.

Figure 1 is a view of a piece of fence including round intermediate line or running 30 wires and similar one piece stay or picket wires, and top and bottom or marginal wires which are oval or oblong in cross-section; the intermediate line or running wires and 35 the stay or picket wires where they cross being connected by a staple-tie, and the ends of the round stay or picket wires being wrapped around said oval or oblong marginal wires;

Fig. 2 is an enlarged cross-section, as the 40 same would appear if taken on the line 2-2 of Fig. 1 looking in the direction of the arrows.

Fig. 3 is an enlarged view of the staple- 45 tie connection for an intermediate line or running wire and a stay or picket wire;

Fig. 4 is an enlarged cross-section of a line or running wire oblong in cross-section, the wires having been formed with rounded 50 top and bottom edges and flat sides, either produced by a rolling or a drawing operation, or flattened after or during the weaving operation;

Fig. 5 is a view similar to Fig. 4 except that the wire exhibits a more definite oval 55 shape in cross-section, the sides of the wire instead of being flat, having a convex surface merging into the rounded edges thereof;

Fig. 6 is a view of a piece of fence including both intermediate and marginal line or 60 running wires which are oval or oblong in cross-section, and stay or picket wires which comprise short sections of round wires, the meeting ends of which are intercoiled or interwrapped around intermediate line or 65 running wires, and with the extreme ends of the outer sections of said stay or picket wires coiled or wrapped around said marginal wires;

Fig. 7 is an enlarged cross-section, as the 70 same would appear if taken on the line 7-7 of Fig. 6 looking in the direction of the arrows; and

Fig. 8 is an enlarged view of the intercoiled or interwrapped ends of the sections 75 of round stay or picket wire around a line or running wire, oval or oblong in cross-section.

Like characters of reference denote corresponding parts throughout the figures. 80

The top and bottom wires of the fence are designated 1 and 2, respectively, and the intermediate line or running wires are designated 3. In Figs. 1, 2 and 3 the stay or picket wires 4 are made of one single piece 85 of round wire extending from one marginal wire to the other and crossing the intermediate line or running wires. The ends of wires 4 are coiled or wrapped around the marginal wires at an angle to the vertical, 90 as at 5, with the line of wrapping at an angle to the vertical, and where said wires 4 cross the wires 3 they are connected by means of staple-ties 6.

In Figs. 6, 7 and 8 the stay or picket 95 wires comprise the top and bottom short sections 7 and 8 of round wire and the intermediate sections 9 of similar round wire. The meeting ends of the sections 9 are intercoiled or interwrapped around the wires 3, 100 as at 10; the upper ends of the sections 7 are coiled or wrapped around the top marginal wire 1, at an angle to the vertical, as at 11; and the lower ends of the sections 8 are coiled or wrapped around the lower 105 marginal wire 2, as at 12.

Experience has demonstrated that the same trouble is experienced where the stay or picket wires are coiled or wrapped around the marginal wires, as is experienced 5 where the stay sections are coiled or wrapped around the intermediate line or running wires. Such trouble briefly stated is this: When the stay or picket wire is coiled or wrapped around a line or running 10 wire, whether the last-mentioned wire is of a larger gage or not, the coil or wrap will open slightly after the pressure of the wrapping or coiling means has been released; so that when pressure is applied, in the direction 15 of the length of the stay or picket wire, whatever the character of that pressure may be, the coil or coils in the stay will become uncoiled or unwrapped and the fence will become loose and sag and permit small 20 animals to work through the meshes, and the fence generally lose its efficiency for turning stock and small animals.

The use of line or running wires in the fence, oval or oblong in cross-section and 25 with their long diameters or wide faces arranged substantially vertically, it has been demonstrated, will not only overcome the above stated objections, but will also, almost if not entirely, prevent slipping of the 30 coiled or wrapped portions along the line or running wires. As an example, if a stay or picket wire, round in cross-section, is coiled or wrapped around a line or running wire, which is oval or oblong in cross-section, approximately two and one-half 35 wraps, the same condition exists as when a rope is wrapped around a winch and tension applied to the ends of the rope. It is common knowledge that a rope and winch 40 have enormous power, and when the winch is turning it requires but a slight pressure on the part of a person who is pulling the rope to lift enormous loads. By the use of line or running wires, oval or oblong in 45 cross-section, I have obtained the same advantage in fence construction, as has been illustrated with the winch. For example—if a stay or picket wire is wrapped two and one-half times around another wire, oval or 50 oblong in cross-section, without increased friction it will have at least five times more strength than if the same stay or picket wire is wrapped around a round wire, due to the fact, as must be obvious, that there 55 are five distinct bendings necessary in the process of pulling the stay or picket wire from the strand, instead of uncoiling one

continuous coil, as where one round wire is coiled around another round wire.

Another advantage that the line or running wires, which are oval or oblong in cross-section, has, as compared with a round wire is, to prevent the stay or picket wire from slipping on the line or running wire. I have stated that when the pressure of the 60 wrapping means on the coil of the stay or picket wire has been released there is a tendency for the coil to unwind or unwrap slightly, producing a slightly larger diameter for the inside of the coil than the outside 65 diameter of the wire on which it is coiled. Applied to a wire oval or oblong in cross-section, with the coil having flat or nearly flat long parallel sides and narrow ends, the ends act to bite into the narrowed top 70 and bottom edges of the oblong wires, and when the coil opens the coils will grip the oval wire very much tighter and much more effectively, than if the coil is wrapped around a wire which is round in cross-section. 80

Therefore, in a fence of the character shown in Fig. 1, the top and bottom wires 1 and 2 are made oval or oblong in cross-section; and the intermediate wires 3, in the 85 fence shown in Fig. 6, as well as the top and bottom wires 1 and 2, are made oval or oblong in cross-section.

It is of no particular advantage to make the stay or picket wires oval or oblong in 90 cross-section; however, it is understood that if it is desired to use such wires, this is comprehended in the present disclosure.

What I claim is:

A wire fence including horizontally arranged top and bottom marginal wires and intermediate wires, the said top and bottom marginal wires being each approximately oblong in cross-section and having 100 their widest faces arranged vertically, and vertically arranged stay-wires having end portions with each of the latter wrapped around the marginal wires with the line of wrapping at an angle to the vertical, the said end portions of the stay-wires being each tightly and closely wrapped a number 105 of times around each of said top and bottom wires so as to form a series of wrappings each having long parallel sides and narrow ends, the ends acting to bite into the narrowed top and bottom edges of the said marginal wires. 110

WILLIAM H. SOMMER.
